Inventor:

Jaroslav Pribyl

UNITED STATES PATENT OFFICE.

JAROSLAV PŘIBYL, OF PRAGUE, CZECHOSLOVAKIA.

GUITAR AND THE LIKE.

Application filed July 26, 1922. Serial No. 577,688.

To all whom it may concern:

Be it known that I, JAROSLAV PŘIBYL, a citizen of the Czechoslovakian Republic, residing at Prague, Czechoslovakia, have invented certain new and useful Improvements in Guitars and the like, of which the following is a specification.

This invention relates to guitars, lutes and the like of the kind provided with two sets 10 of strings of which one is carried underneath its finger-board so that it can be stopped by the thumb while the other set is stopped by the fingers in the usual manner. In known instruments of this kind the two 15 string sets are carried in juxtaposition, an arrangement which prevents the thumb from reaching the lower strings with sufficient freedom. The nuts moreover, are arranged so that the effective length of both 20 sets of strings is equal.

According to the present invention the two sets of strings are arranged so as to overlap at the head of the instrument whence they diverge towards two tail pieces 25 arranged in juxtaposition on the belly. Owing to the overlapping position of the two sets of strings, the thumb will be able to reach conveniently a greater number of strings, the compass of the instrument being 30 thereby greatly enlarged. This effect is moreover enhanced by arranging the nut for the lower strings so as to increase the effective length of the latter relative to the upper set by one semi-tone, an arrangement which 35 is known per se in connection with instruments having two sets of strings carried in juxtaposition at the same side of the finger-board.

Fig. 1 of the accompanying drawings represents a front view of the instrument, 40 Fig. 2, a side view of the same, and Fig. 3, a rear view of the neck.

A guitar or lute is fitted with a neck *h* having on the top side a finger-board 1 and 45 on the underside a finger-board 2. Two sets of strings 3 and 4 are provided, one for each

finger-board. The strings are carried from tail pieces 5 and 6, arranged side by side on the belly *b*, to the head *h* where they are connected to pegs *s* in the usual manner and 50 where the two sets of strings overlap, the strings 3 being arranged above the finger-board 1 and the strings 4 below the finger-board 2. The strings 3 are the treble strings and are stopped by the fingers of the 55 left hand, whereas the strings 4 are the bass strings and are stopped by the thumb. The effective length of the bass strings is preferably greater than that of the treble strings, for which purpose the nut *h* for the former 60 is arranged farther away from the tail piece 6 than the nut 7 for the latter from the tail piece 5.

The tail pieces 5 and 6 may be combined 65 into one.

I claim:

1. The combination with a guitar or an instrument having a belly, of a neck having two finger-boards, one at the top and the other at the underside, said finger-boards being arranged so that two sets of strings can be carried to an overlapping portion on the neck from tail pieces arranged in juxtaposition on the belly, one set above the upper finger-board and the other set below the 75 lower finger-board, substantially as and for the purpose set forth.

2. The combination with a guitar or an instrument having a belly, of a neck and two finger-boards, one at the top and the other 80 at the underside, said finger-boards being arranged so that two sets of strings can be carried to an overlapping portion on the neck from tail pieces arranged in juxtaposition on the belly, one set above the upper 85 finger-board and the other set below the lower finger-board, and nuts arranged so that the effective length of the lower set of strings is greater than that of the upper set, substantially as and for the purpose set 90 forth.

JAROSLAV PŘIBYL.
